CLAIM

The ornamental design for a tennis ball carrier, as shown and described.

DESCRIPTION

FIG. 1 is a front perspective view of a tennis ball carrier showing my new design;

FIG. 2 is a front elevational view thereof;

FIG. 3 is a rear elevational view thereof;

FIG. 4 is a right side elevational view with the left side being a mirror image thereof;

FIG. 5 is a top plan view thereof; and,

FIG. 6 is a bottom view thereof.

In FIGS. 5 and 6 the straps are shown broken away to indicate variable length.
